UNITED STATES PATENT OFFICE.

PAUL P. HERBERG AND PETER H. CLAUSSEN, OF GALE, WISCONSIN.

GRAIN-SEPARATOR.

SPECIFICATION forming part of Letters Patent No. 255,982, dated April 4, 1882.

Application filed June 17, 1881. (No model.)

To all whom it may concern:

Be it known that we, PAUL P. HERBERG and PETER H. CLAUSSEN, both of the town of Gale, in the county of Trempealeau and State of Wisconsin, have invented a certain new and useful Improvement in Grain-Separators, of which the following is a specification.

Our invention relates to that class of machines in which the grain is separated from its accompanying refuse by means of a blast and suitable screens; and it consists of certain minor improvements, as hereinafter described and claimed.

In the accompanying drawings, Figure 1 represents an elevation of one side of a grain-separator having our improvements applied thereto. Fig. 2 is a longitudinal vertical section through the center of the machine and improvements. Fig. 3 represents an enlarged 20 side elevation of the elevator-head and sack-holder, and Fig. 4 is a sectional plan of the same.

A denotes the frame of the machine, arranged to support and accommodate the several operating parts.

B is the hopper, into which the grain to be cleaned is shoveled.

a represents a sliding gate in the hopper for regulating the feed of the grain to the machine. 30 D is the shoe, suspended between the sides of the frame by straps in the usual manner.

Q represents an elevator or conveyer box, which is not here specifically described, as it is designed to make this the subject of a separate application. This elevator-box is pivotally and removably attached at one end to the

machine-frame, and the other or elevated end has the ends of two ropes, R, attached to a roller, S. This roller S is pivoted to the top of the machine-frame, and is provided with a ratchet-wheel, s, that engages with a pawl, j', for adjustably suspending the said elevator-box at any desired inclination.

The elevator is of a length to reach to a horizontal position with the roller S when raised 45 for attaching a sack. The position of the ropes R when the elevator is thus raised is as seen in Fig. 3. When in its lower position the ropes R will assume the angle shown in Fig. 1.

At the head of the elevator-box a sack-holder 50 is arranged, which consists of a square spout, T, into which the cleaned grain is dumped by the buckets of the endless apron. As it is designed to make this sack-holder the subject of a separate application, its peculiar construction 55 is not now set forth.

Having thus described our present improvements, what we claim therein is—

The combination, with a grain-separator and a grain-elevator provided with a sack-holder, 60 of the ropes R, roller S, ratchet-wheel s, and pawl j' for adjustably suspending the elevator-head, substantially as set forth.

The above specification signed by us, in the presence of two witnesses, this 8th day of June, 65 1881.

PAUL P. HERBERG.
PETER H. CLAUSSEN.
